UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

INTERMITTENT INDUCTIVE TRAIN CONTROL SYSTEM

Application filed October 19, 1929. Serial No. 400,867.

This invention relates to automatic train control systems, and more particularly to a system of the intermittent inductive type designed for use on railroads of the electric propulsion type.

In the application of intermittent inductive train control to railway systems of the electric propulsion type, it has been experienced that a sudden change in the propulsion current where this propulsion current is direct current, or an exceptionally large current flow in the track rails and third rail where the propulsion current is alternating in character, affects the inductive receiving train control apparatus, and at times causes a false and unauthorized brake application. In accordance with the present invention it is proposed to so organize the receiving coils of the car-carried apparatus that the induction of voltage in the receiving apparatus is neutralized, this preferably being obtained by employing two receiving coils so connected in series that the induction of voltage therein due to propulsion current flowing in the track rails, the third rail or wires parallel thereto, are equal and opposite.

Other objects, purposes and characteristic features of the invention reside in the provision of car-carried apparatus applicable to electric locomotives in which a controller and engineer's brake valve is located at each end of the electric locomotive, which includes two separate receivers located on opposite sides of the locomotive the proper one of which is cut into service when the brake valve and controller handles at a particular end of the locomotive are being used.

Other objects, purposes and characteristic features of the invention will in part be obvious from the accompanying drawings and will in part be described hereinafter.

In describing the invention in detail reference will be made to the accompanying drawings in which:

Fig. 1 shows in a conventional manner the car-carried and trackway apparatus of one system embodying the present invention;

Fig. 2 shows an enlarged side view of the receivers shown in Fig. 1 of the drawings;

Fig. 3 shows the core and coil structure of the receiver shown in Fig. 2; and

Fig. 4 shows the acknowledging apparatus of a system otherwise the same as that shown in Fig. 1 of the drawings.

Referring to Fig. 1 of the drawings, the embodiment of the invention illustrated has been shown applied to a railway system having track rails 5 divided by insulating joints 6 into blocks, at the entrance to each of which is located a signal S, and of which system for convenience a portion of the blocks J and K only have been shown. Although these blocks are insulated from each other by insulating joints 6, these blocks are electrically connected for permitting flow of direct propulsion current by the balanced impedance bonds IB, as shown. At the entrance to each block and just in the rear of the signal S is located an inductor I comprising a core 7 constructed of laminated magnetic material and having a coil 8 on the back yoke thereof, this coil 8 being closed in a circuit of low resistance under clear traffic conditions as conventionally shown by the contacts 9 and 10 of the polar neutral line relay LR.

The electric locomotive on which the car-carried apparatus is mounted has been conventionally illustrated by the wheels and axles 12. In the front cab of the electric locomotive is provided the usual engineer's brake valve and controller (not shown), a whistle valve W¹, and a cut-in device CD¹ including the lever L¹. In the rear cab is provided similar apparatus which includes the whistle valve W² and the cut-in device CD². In this connection it may be pointed out that the cut-in devices CD¹ and CD² and contacts associated therewith function in a manner more particularly described in the operation of the system hereinafter, and also includes valves so organized that the device EPV is cut-out of service pneumatically unless one of the cut-in devices CD¹ or CD² is in its cut-in (namely the No. 1) position.

The car-carried apparatus also includes the relays R¹, R² and R³, an acknowledging stick relay AS, an acknowledging relay AcR and a time element relay TR. The car-car-

ried apparatus also includes a ballast lamp BL, two acknowledging push buttons Ack^1 and Ack^2 , and a reset push button RS only accessible from the ground. In order to more clearly understand the particular embodiment of the invention illustrated it is deemed expedient to consider the operation of the system.

Operation.—With the car-carried apparatus in its normal clear position, as it would be after having been reset by operation of the reset push button RS, the primary coil P^1 is energized through the following circuit:—beginning at the terminal B of a suitable car battery, wire 15, primary coil P^1 , wires 16 and 17, contact 18 of the cut-in switch CD^1 , wire 19, contact 20 of the cut-in switch CD^2 , wires 21 and 22, ballast lamp BL, wire 23, winding of the relay R^3 to the other terminal C of said car battery. The flow of current in this circuit maintains the relay R^3 energized, this relay R^3 serving as a check relay for indicating the flow of an adequate amount of current in the primary coil P^1 to assure functioning of the system, and also serving as a resistance unit for obtaining a voltage (the resistance drop over this relay) for maintaining the low voltage control relay R^1 energized.

It may be pointed out that the ballast lamp BL conventionally represents suitable means for maintaining the current flowing in the primary coil P^1 constant and at a definite value irrespective of fluctuation of battery voltage. This unit BL may be a lamp having a very high positive temperature coefficient of resistance, so that a slight increase of current flow therein will increase the temperature and therefore the resistance to an extent to limit such current flow. This unit BL, on the other hand, may be an electrically operated changeable resistance, such as a carbon pile operated by an electromagnet which produces a similar effect.

With the relay R^3 energized there is a small potential drop over the winding of this relay R^3 , and this potential drop is applied to the relay R^1 through the following circuit:—beginning at the plus side of the relay R^3 , wires 23, 24, and 25, coils S^1 of the right hand receiver RR, wires 26 and 27, contact 28 of the cut-in device CD^1 , wires 29 and 30, winding of the relay R^1 , wires 31 and 32, front contact 33 of the relay R^1 , to the terminal C of the car battery. The flow of the current in this circuit will maintain the relay R^1 energized and by reason of closure of its front contact 33 will maintain the relay R^2 energized through the following circuit:—beginning at the terminal B of said car battery, wire 35, front contact 36 of the relay R^2 , wire 37, winding of the relay R^2 , wire 38, contact 33 of the relay R^1 , to the other terminal C of the car battery.

With the relay R^2 energized the acknowl-

edging relay AS (picked up in a manner explained hereinafter) is maintained energized through the following circuit:—beginning at the terminal B of the car battery, front contact 35 of the relay R^2 , wires 40 and 41, front contact 42 of the relay AS, wire 44, the lower winding 43 of this relay to the other terminal C of the car battery. It is thus seen that the relay AS is held energized by the relay R^2 , that the relay R^2 is held energized by a circuit including a front contact of the relay R^1 , and that the relay R^1 derives its energy from the potential drop across the relay R^3 .

Under these conditions of the relays, the electropneumatic brake applying valve EPV is energized through the following circuit:—beginning at the terminal B, back contacts 45 of the acknowledging relay Ack^1 , wires 46 and 47, front contacts 48 of the relay R^3 , wire 50, front contact 51 of the acknowledging relay AS, wire 52, winding of the valve EPV, to the other terminal C of the car battery.

Let us now assume that the car 12 is travelling from left to right in the block J, and that the coil 8 of the track inductor I is open circuited, because the line relay LR is either energized to its left hand position or is deenergized. As the car 12 passes the inductor I the right hand receiver RR cooperates with the inductor I, and during its passage over this inductor produces an increase of flux through the secondary coils S^1 , the turns in the coils S^1 being in such a direction that the voltage induced in these coils S^1 due to this increase in flux opposes the voltage normally applied to the control relay R^1 , so that the energizing current for the relay R^1 falls to such a value that its contacts 33 will open. It is of course understood that a voltage of the opposite polarity will be induced in the secondary coils S^1 as the receiver RR leaves the inductor. This second wave of the induced voltage is however of no importance in that if the relay R^1 has dropped, its energizing circuit including its stick contact is broken. Since the relay R^1 is a stick relay the opening of its stick contact 33 will prevent picking up of this relay when the induced voltage ceases.

Let us first assume that the engineer was alert and has in the mean time depressed his acknowledging push button Ack^1 . Dropping of the relay R^1 effects deenergization of the relay R^2 , and as this relay R^2 assumes its retracted position the relay R^1 is permitted to again pick up through the following circuit:—beginning at the plus side of the winding relay R^3 , wires 23, 24 and 25, secondary winding S^1 , wires 26 and 27, contact 28 of the cut-in device CD^1 , wires 29 and 30, winding of the relay R^1 , wires 31 and 55, back contacts 56 of the relay R^2 , wire 57, to common return wire 136

C connected with the other side of the car battery. The completion of this circuit effects quick restoration of the relay R¹, and if the engineer has manifested his vigilance 5 and has operated his push button Ack¹ as assumed, he has thereby energized the acknowledging relay AcR. The closure of the front contact 45 of this relay AcR has maintained the lower winding of the relay AS energized, and restoration of the relay R¹ to its normal position completes the following 10 circuit for the relay R²—beginning at the terminal B, front contact 45 of the relay AcR, wires 60, 40 and 37, winding of the 15 relay R², wire 38, front contact 33 of the relay R¹, to common return wire C connected to the other side of the car battery.

The relay R² is thus returned to its normal energized position, because the engineer 20 has manifested his vigilance and has maintained the acknowledging relay AcR energized through the following circuit—beginning at the terminal B of the car battery, wire 61, winding of the relay AcR, wire 25 62, winding 63 of the relay TR, wires 64, 65 and 66, acknowledging push button Ack¹, to common return wire C and a grounded part of the car, such as the truck, as conventionally illustrated. It should be 30 noted that the device EPV relies for its current flow on a circuit through either the back contact 45 of the relay AcR or through wire 67, contact 68 of relay TR and wire 69. It is thus apparent that the engineer 35 must operate his push button Ack¹ to energize the relay AcR for a very short time only while passing over the inductor I, because this depression of the push button Ack¹ also causes heat to be generated by the 40 coil 63 of relay TR, which heating opens the circuit for the device EPV at the contacts 68 of the thermal relay TR, if the engineer pushes the acknowledging button Ack¹ too long. The acknowledging apparatus 45 is thus protected against misuse, such as permanent tying down.

It has just been explained how the relay R¹ is returned to its normal attracted position. Attention is now directed to the fact 50 that during the time that the relay R² is in its deenergized position with the relay AcR in its energized position and the push button Ack¹ depressed the audible whistle W¹ is sounded through the following circuit— 55 beginning at the terminal B, front contact 45 of the relay AcR, wires 60 and 40, contact 36 of the relay R² in its retracted position, wire 70, contact 71 of the cut-in device CD¹, wire 72, winding of the whistle 60 valve W¹, which is sounded while this winding is energized, wires 73 and 66, through the push button Ack¹ to common return wire C. The sounding of the whistle W¹ attracts the attention of the fire-man, so that 65 the fire-man is aware of the fact that the

train has passed by an inductor in its stop condition.

Let us now assume that during the passage of the train 12 by the inductor I the engineer has not been alert, but was incapacitated or asleep, and let us observe what effect momentary dropping of the relay R¹ will have on the car-carried apparatus. Dropping of the relay R¹ is only momentary in that it effects dropping of the relay R² which dropping of the relay R² restores the relay R¹, but this dropping of the relay R¹ also effects deenergization and dropping of the relay AS, in that the lower winding of the relay AS derives its energizing current from the front contact 36 of the relay R² through the medium of the wire 35. Obviously, deenergization of the relay AS also effects deenergization of the device EPV in that its energizing circuit thereof will be broken at the contact 51. Dropping of the device EPV will of course effect a brake application which will bring the train to a stop.

With the relay AS once assuming its deenergized position it can not be restored unless the train is brought to a stop and the reset push button RS is operated simultaneously with the operation of one of the acknowledging push buttons Ack¹ or Ack². The engineer must therefore alight to the ground and depress the push button RS while his fireman depresses the push button Ack¹ thereby completing the following circuit—beginning at the terminal B of the car battery, front contact 75 of the relay AcR, wire 76, upper winding 77 of the relay AS, wire 78, push button RS, wire 79 to a ground portion of the car, wire 73¹ push button contact Ack¹, wire 74 to the common return wire C. Obviously with the relay AS restored to normal the car-carried apparatus can be brought back to its normal condition in which the device EPV is energized.

Since the reset push button RS is only accessible from the ground the engineer is penalized for his failure to operate the acknowledging push button Ack¹ or Ack² in time, in that he must bring the train to a stop, must alight to the ground and must in cooperation with the fireman operate the push button RS simultaneously with the fireman's operation of the acknowledging push button Ack¹ or Ack². In this connection, if desired, a speed governor may be 110 added which is driven from the axles of the vehicle and which is provided with a contact closed only when the train is moving at a speed below, say two miles per hour, and this contact may be substituted for the reset 115 contact RS. In this latter case the penalty resides in the requirement of the engineer to bring the train substantially to a stop.

The contact 80 of the cut-in device CD¹ is associated with the master controller in 120

the engineer's cab and is of little importance insofar as the present invention is concerned.

Since the apparatus functions the same irrespective of which end of the locomotive leads, it is deemed unnecessary to describe the operation of the system with the cut-in device CD_2 cut-in, and with the cut-in device CD_1 cut-out.

- 20 One of the features of the present invention resides in the construction of the receivers RR and LR . It should be noted that these receivers have a primary coil on the back yoke of the inverted U shaped core 83, and that this yoke is depressed in the middle (see Fig. 3 of the drawings), so as to form a very compact structure, which core and coils may be housed in a rather small non-magnetic metal housing 84 (see Fig. 2 of the drawings). This non-magnetic housing 84 is adjustably secured to large pins 85 projecting sidewise from the truck, by the provision of blocks 86 adapted to slide vertically on the brackets 87. These blocks 86 support the brackets 87 through the medium of threaded thrust pins 88 having lock nuts 89 thereon, and these thrust pins 88 are screw threaded into the brackets 87. Attention is also directed to the fact that the wires leading to the primary coil P^1 and the secondary coils S^1 pass through the conduit 90 into the junction box 91. Attention is further directed to the fact that the magnetism passing through the primary coil P^1 passes through the secondary coils S^1 vertically in opposite directions, so that the turns in the secondary coils must be opposite, in order that the inductive effect due to a change in the magnetism derived from the primary coil P^1 may be cumulative. For this reason, no inductive effect due to current flowing in wires or rails parallel to the track rails will be experienced in the secondary circuits, in that the magnetic lines will pass through the secondary coils S^1 in such a direction that the voltages induced in these secondary coils S^1 are opposite, and neutralized, in so far as they affect this secondary circuit. In other words, the flow of either alternating current or an abrupt change in the flow of direct current in the track rails, or in the third rail of the railway system, will not materially affect the flow of current in the secondary coils S^1 , and therefore the system embodying the present invention is such as to be immune to propulsion current.

Applicant has therefore shown one embodiment of his invention which is immune to propulsion current, and which embodies essential features for application of the system to an electric locomotive having a controller and an air brake valve at each end thereof. Attention is again directed to the fact that the electro pneumatic valve EPV

is pneumatically cut-in and capable of effecting a brake application only when either of the cut-in devices CD^1 or CD^2 is in its cut-in position. This electropneumatic valve EPV is of course one of the normally energized type and is constructed to vent the brake pipe, and effect a brake application, when deenergized.

Modified construction.—In Fig. 4 of the drawings have been shown acknowledging push buttons Ack^3 and Ack^4 , which may be substituted for the acknowledging push buttons Ack^1 and Ack^2 together with the thermal relay TR and the acknowledging relay AcR . In order to simplify the description of the system when modified to omit the time element thermal relay TR and the acknowledging relay AcR , the wires leading from the apparatus of Fig. 4 of the drawings have been numbered exactly the same as the corresponding wires in the complete system shown in Fig. 1 of the drawings. The modified construction shown in Fig. 4 obtains the same results as does the corresponding apparatus as shown in Fig. 1, and in order to bring out this functioning of the apparatus, only the similarities between the two structures will be pointed out.

Referring to Fig. 1 it will be noted that the contact 68 removes the terminal B from the wire 47 only after an interval of delay after one of the push buttons Ack^1 and Ack^2 have been depressed. Similarly, the terminal B is removed from the wire 47 in Fig. 4 of the drawings only after an interval of delay after depression of one of the push buttons Ack^3 or Ack^4 , because the normally closed contacts 95 and 96 have their opening retarded by dash pots 97 and 98, these contacts being urged to their open position by tensioned springs 99 and 100. Similarly, the wires 60 and 76 in Fig. 1 are connected to the terminal B immediately upon depression of the push buttons Ack^1 or Ack^2 in Fig. 1 of the drawings, as is also true in Fig. 4 of the drawings, where depression of the push buttons Ack^3 or Ack^4 closes the contacts 101—102 or 103—104, respectively. Similarly wires 73 and 73² are connected to ground during acknowledgement in Fig. 4 of the drawings, as is also true of Fig. 1.

Having thus shown and described one rather specific embodiment of the present invention and having shown one way in which the invention may be modified, it is desired to be understood that the particular circuit arrangement and devices selected have been selected for the purpose of facilitating description of the invention, rather than its scope or the exact construction preferably employed in practicing the same, and that various changes, modifications and additions may be made to adapt the invention to the particular system or locomotive

to which the invention is to be applied, all without departing from the spirit or scope of the invention or the idea of means underlying the same, except as demanded by 5 the scope of the following claims.

What I claim as new is:—

1. Train control apparatus immune to the flow of propulsion current comprising; a receiver consisting of a primary coil on the back yoke of an inverted U-shaped core; a secondary coil on each leg; said secondary coils being connected in series so that a change of flux in said core will produce voltages in said secondary coils which are cumulative; an energizing circuit for said primary coil including a source of direct current and a check relay; a control relay having a stick contact; a secondary circuit including in series said control relay, its stick contact, said secondary coil and said check relay; and trackway means for changing the reluctance of the magnetic circuit including said core; whereby the voltage drop over said check relay serves as a source of current to maintain said control relay energized, and whereby propulsion currents cannot induce a voltage in said secondary circuit.

2. Train control apparatus immune to the flow of propulsion current comprising; a receiver consisting of a primary coil on the back yoke of an inverted U-shaped core disposed lengthwise of the train; a secondary coil on each leg said secondary coils being connected in series so that a change of flux in said core will produce voltages in said secondary coils which are cumulative; an energizing circuit for said primary coil including a source of direct current and a check relay; a control relay having a stick contact; a secondary circuit including in series said control relay, its stick circuit, said secondary coils and said check relay; and trackway means for changing the reluctance of the magnetic circuit including said core; whereby the voltage drop over said check relay serves as a source of current to maintain said control relay energized, and whereby propulsion currents flowing in conductors substantially parallel to the track rails cannot induce a voltage in said secondary circuit.

3. Train control apparatus immune to the flow of propulsion current comprising; a receiver consisting of a primary coil on the back yoke of an inverted U-shaped core; a secondary coil on each leg; said secondary coils being connected in series so that a change of flux in said core will produce voltages in said secondary coils which are cumulative; an energizing circuit for said primary coil including a source of direct current and a check relay; a control relay having a stick contact; a secondary circuit

including a series said control relay, its stick contact, said secondary coils and said check relay; and an inductor at the entrance to each block located so as to magnetically cooperate with said receiver upon passage of the car carrying said apparatus, consisting of a core of iron when in its active condition.

4. Train control apparatus immune to the flow of propulsion current comprising; a receiver consisting of a primary coil on the back yoke of an inverted U-shaped core; a secondary coil on each leg; said secondary coils being connected in series so that a change of flux in said core will produce voltages in said secondary coils which are cumulative; an energizing circuit for said primary coil including a source of direct current and a check relay; a control relay having a stick contact; a secondary circuit including in series said control relay, its stick contact, said secondary coils and said check relay; and an inductor at the entrance to each block located so as to magnetically cooperate with said receiver upon passage of the car carrying said apparatus, consisting of a core of iron when in its active condition, and a coil on said inductor core closed in a circuit of low resistance under clear traffic conditions.

5. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for said control relay; a repeater relay controlled by said control relay; an acknowledging relay having a stick contact; a stick circuit for said acknowledging relay including said last mentioned stick contact and a front contact of said repeater relay; a normally energized electrically operated brake controlling valve which if de-energized applies the brakes of the vehicle; and a circuit for energizing said valve including front contacts of said check relay and front contacts of said repeater relay in series.

6. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for said control relay; a repeater relay controlled by

said control relay; an acknowledging relay having a stick contact; a stick circuit for said acknowledging relay including said last mentioned stick contact and a front of said repeater relay; an auxiliary circuit for said acknowledging relay including a manually controllable contact, a normally energized electrically operated brake controlling valve which if de-energized applies the brakes of the vehicle; and a circuit for energizing said valve including front contacts of said check relay and front contacts said repeater relay in series.

7. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for said control relay; a repeater relay controlled by said control relay; an acknowledging relay having a stick contact; a stick circuit for said acknowledging relay including said last mentioned stick contact and a front of said repeater relay; an auxiliary circuit for said acknowledging relay including a manually controllable contact; a normally energized electrically operated brake controlling valve which if de-energized applies the brakes of the vehicle; and a circuit for energizing said valve including front contacts of said check relay and said repeater relay connected in series, and an electrically operated audible signal sounded momentarily and only when said manually controllable contacts are closed and said receiver passes an active inductor.

8. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for the circuit including said control relay and said secondary coil in series; a repeater relay controlled by said control relay; an acknowledging relay having stick contacts; a stick circuit for said acknowledging relay including said last mentioned stick contacts and front contacts of said repeater relay; a normally energized electrically operated brake controlling valve which if de-energized applies the brakes of the vehicle; and a circuit for energizing said valve including front contacts of said check relay and front contacts of said repeater relay in series, and an

audible signal sounded upon deenergization of said repeater relay.

9. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for said control relay; a repeater relay controlled by said control relay; an acknowledging relay having stick contacts; a stick circuit for said acknowledging relay including said last mentioned stick contacts and a front of said repeater relay; an auxiliary circuit for said acknowledging relay including a manually controllable contact; a normally energized electrically operated brake controlling valve which if de-energized applies the brakes of the vehicle; and a circuit for energizing said valve including front contacts of said check relay and said repeater relay connected in series, and an electrically operated audible signal sounded momentarily and only when said manually controllable contacts are closed and said receiver passes an active inductor.

10. Car-carried apparatus for automatic train control systems comprising; an inductive vehicle carried receiver including a primary winding and a secondary winding; a source of direct current; a check relay; a circuit including said check relay, said primary coil and said source in series; a control relay connected in series with said secondary winding and across said check relay, so that the voltage drop over said check relay serves as a source of current for said control relay; a repeater relay controlled by said control relay; an acknowledging relay having stick contacts; a stick circuit for said acknowledging relay including said last mentioned stick contacts and a front contact of said repeater relay; an auxiliary circuit for said acknowledging relay including manually controllable contacts, means for deenergizing said electrically operated valve if said manually controllable contacts are kept closed for more than a predetermined time; a normally energized electrically operated brake controlling valve which if de-energized applies the brakes of the vehicle; and a circuit for energizing said valve including front contacts of said check relay and said repeater relay in series, an electrically operated audible signal sounded momentarily and only when said manually controllable contacts are closed and said receiver passes an active inductor.

11. Car-carried apparatus for automatic train control systems comprising; an electro-

- pneumatic valve normally energized and which if de-energized applies the brakes of the train; means controlled from the trackway for effecting de-energization of said valve and effective for a time only; and acknowledging means for preventing deenergization of said valve and protected against misuse comprising; two normally deenergized relays the first of which is quick acting and the second of which is slow acting, a back contact of said slow acting relay included in series with the circuit of said valve, a front contact of said quick-acting relay for completing an auxiliary circuit for maintaining said electro-pneumatic valve energized irrespective of its control from the trackway, and an energizing circuit for said two relays including a manually operable contact.
12. Train control apparatus immune to the flow of propulsion current comprising; a receiver consisting of a primary coil on the back yoke of an inverted U-shaped core; a secondary coil on each leg; said secondary coils being connected in series so that a change of flux in said core will produce voltages in said secondary coils which are cumulative and so that equal vertical flux changes in the two legs will induce equal and opposite voltages in said secondary coils in series, a normally energized stick brake control device controlled by said secondary coils which if once deenergized remains deenergized until specially restored, manually operable means which if actuated prevents deenergization of said device in spite of its control by said secondary coils, and means for protecting said manually operable means against misuse.
13. Car-carried apparatus for automatic train control systems comprising; an electro-pneumatic valve normally energized and which if de-energized applies the brakes of the train; means controlled from the trackway for effecting de-energization of said valve and effective for a time only; and acknowledging means for preventing deenergization of said valve and protected against misuse comprising; two normally deenergized relays the first of which is quick acting and the second of which is thermally operated, a back contact of said thermally operated relay included in series with the circuit of said valve, a front contact of said quick-acting relay for completing an auxiliary circuit for maintaining said electro-pneumatic valve energized irrespective of its control from the trackway, and an energizing circuit for said two relays including a manually operable contact.

In testimony whereof I affix my signature.
CHARLES S. BUSHNELL.
